(57) **CLAIM**

The ornamental design for an orthotic insole with attachable angle insert, as shown and described.

DESCRIPTION

FIG. 1 is a top perspective view of an orthotic insole with attachable angle insert, showing our new design;

FIG. 2 is a bottom perspective view thereof;

FIG. 3 is a top view thereof;

FIG. 4 is a bottom view thereof;

FIG. 5 is a side view thereof;

FIG. 6 is another side view thereof;

FIG. 7 is a front view thereof;

FIG. 8 is a rear view thereof;

FIG. 9 is a bottom perspective view thereof with the angle insert removed; and,

FIG. 10 is a bottom perspective view of the angle insert shown separately for ease of illustration.

1 Claim, 4 Drawing Sheets
